CARBURETOR

Otto Henning, Detroit, Mich., assignor to Carter Carburetor Corporation, St. Louis, Mo., a corporation of Delaware

Application May 18, 1934, Serial No. 726,274

9 Claims. (Cl. 261—65)

This invention relates to carburetors for internal combustion engines and more particularly to devices for controlling closing movements of the throttle to prevent roughness in the operation of the engine under certain conditions.

Prior to my invention, the operation of internal combustion engines, more especially those mounted in rubber, was frequently uneven. If the engine is operating at a comparatively high speed, the torque developed is high and there is a tendency for the engine to move to one side, generally to the right. If now, the operator closes the throttle quickly, shutting off the supply of gasoline to the engine, the speed will be rapidly decreased and the engine will tend to move to the opposite side. When the speed is decreased rapidly this movement in the opposite direction is very rapid and results in a shock. This shock is not taken up entirely by the rubber mountings and is thence transmitted to the various parts of the car providing discomfort to the occupants and strain on the entire automobile.

I have found that this shock could be prevented by a means for resisting the rapid closing action of the throttle, thus decreasing the gasoline supply to the engine at a slow rate, whereby the torque and the speed are decreased more slowly allowing the engine to move to its new position without a shock to the car.

In accomplishing the above object I have provided a dash pot constructed in such a way as to allow rapid opening of the throttle, but preventing rapid closing.

A better understanding of my invention will be had by referring to the drawings in which:

Figure 1 is a side elevation of a down-draft carburetor with my invention added thereto, parts being broken away and others shown in section.

Figure 2 is a view similar to that in Figure 1 of the lower portion of the carburetor, parts being removed or broken away to show other parts more clearly.

Figure 3 is an end elevation of the carburetor, parts being broken away.

Figure 4 is an enlarged sectional view of the plunger as shown in Figure 1.

Figure 5 is a detail view showing the same parts as shown in the lower part of Figure 1, but in a different operating position.

The reference numeral 1 refers to the body of a down-draft carburetor of well known design and structure, having the customary float bowl 2, air horn 3 containing choke valve (not shown) operated by lever arm 4 and choke wire 5. The carburetor contains the usual float mechanism

already well known to the art and not shown in the drawings.

The throttle valve 6, shown by dotted lines in Figure 1, is mounted on a shaft 7 and is operated manually by the lever arm 8, also mounted on the shaft 7, and the link 9 attached by conventional means thereto. Loosely mounted near the outer extremity of the shaft 7 is an arm 10, having a downwardly extending ear 11 near the lower end of which is a hole 12 and near the upper end a hole to which the link 9 is attached. The arm 10 has a forwardly projecting lug 13 extending from its upper edge. At the extremity of the shaft 7 a lever 14 is rigidly mounted. The lever 14 is of well known design. The lever 14 and the lever 10 are interconnected by means of a spring 50, one end of which is hooked into the hole 12 and the other end into a hole 51 in the lever 14 as shown in Figures 1 and 3.

The lever 14 is connected to the rocker arm 16 by the link 15. The rocker arm 16 is connected to the piston 17 of the accelerating pump diagrammatically indicated at 63 by the link 18. A spring, diagrammatically indicated at 60, is connected to the throttle operating mechanism as for instance to the pin 61, the other end being anchored as at 62, for yieldably closing the throttle.

The bracket 20 is held in position with relation to the body of the carburetor by means of screws 21. In the bracket 20 is a shaft 22 on which is loosely mounted the rocker arm 23 to one end of which is connected the link 19 and to the other end the link 24. The link 24 is in turn connected to the plunger shaft 25.

The lower end of the shaft 25 contains a vertical passage 26 relatively large in diameter with relation to the shaft. The upper end of passage 26 is made smaller in diameter forming the valve seat 27 and the still smaller passage 28. Drilled horizontally across the diminished passage 28 is a passage 29 extending through the shaft 25.

A ball check valve 30 is held in position by the pin 31. Below the pin 31 a passage 32, of smaller diameter than that of passage 29, is drilled horizontally into the passage 26. Riveted over at the lower extremity of the plunger shaft 25 are two metal washers 33 which secure the leather plunger 34. The plunger assembly is contained in a housing 35 mounted in the under side of the float bowl 2 by means of threads 38 and made gasoline tight by the gasket 39. The floor 36 of the housing 35 has an annular extension 37 raised to serve as a stop for the plunger, thus preventing the crushing of the plunger leather 34 against

the floor 36 of the housing when the plunger is lowered. The plunger shaft 25 passes through a passage 40 of substantially larger diameter than the plunger shaft. This passage 40 is in the floor 5 of the float bowl 2.

It will be noted that the rocker arm 23, as shown in Figure 1, has the right side or that to which the plunger is connected much longer than the left side or that to which the lever 10 is joined through the link 19. The plunger will thus travel its full stroke while the lever 10 travels through a comparatively small arc, approximately 20 degrees.

In operation, when the throttle valve 6 is opened manually the lever 14 is rotated clockwise with respect to Figure 1 raising the link 15 and operating the accelerating pump as in previous constructions. As the lever 14 rotates clockwise the tension on the spring 50 is increased rotating the 10 lever 10 in a clockwise manner, lowering the link 19. With respect to Figure 1 the right side of the rocker arm 23 is thereby lowered and the left side raised. Consequently the plunger shaft 25 is correspondingly lifted. This upward motion 20 allows the ball check valve 30 to open admitting gasoline from the bowl via passages 40, 29, 32 and 26, respectively to the under side of the plunger. As the throttle is farther opened after the plunger has reached the top of its stroke, the lever 14, 30 rotation thereof being continued in a clockwise direction, leaves its contact with the lug 13 and the lever 10 is stationary.

On closing the throttle, the lever 14 is rotated in a counterclockwise manner with respect to 35 Figure 1. As shown in Figures 1 and 3 the edge of lever 14 contacts the lug 13 when within approximately 20 degrees of closed position rotating the lever 10 in a counterclockwise manner with respect to Figure 1, raising the link 19. Thereby, 40 the plunger shaft 25 is lowered by means of the rocker arm 23. The lowering motion of the plunger causes the pressure of the gasoline to close the ball check valve 30 against its seat 21. The only outlet for the gasoline contained in the 45 housing 35 below the plunger is the comparatively small passage 32. The slow rate of flow of gasoline through the restricted passage 32 prevents the plunger from being lowered rapidly which in turn prevents rapid counter-clockwise motion of levers 10 and 14. Lever 14, being rigidly mounted 50 on the throttle valve shaft 7, rapid closing of the throttle valve 6 is resisted during approximately the last 20 degrees of its closing.

The invention is not limited in details to the 55 structure shown but may be modified in various respects as will occur to those skilled in the art and the exclusive use of all such modifications that come within the scope of the appended claims is contemplated.

60 I claim:

1. A dash pot plunger comprising a shaft, said shaft having a longitudinal passage extending into one end thereof, a reduced portion being formed on the exterior of said shaft near said 65 last named end thereof, the inner portion of said passage being of smaller diameter than the outer portion, the junction of the two portions forming a valve seat, a valve for closing said passage at said valve seat, a transverse bore in said shaft connecting with the smaller portion of said first 70 named bore, and a piston mounted on said reduced portion of said shaft and spaced longitudinally of said shaft from said transverse bore, the end of said shaft being riveted over to hold 75 said piston in position.

2. A dash pot plunger comprising a shaft, said shaft having a longitudinal passage extending into one end thereof, a reduced portion being formed on the exterior of said shaft near said last named end thereof, the inner portion of said passage 5 being of smaller diameter than the outer portion, the junction of the two portions forming a valve seat, a ball check valve for closing said passage at said valve seat, a transverse bore in said shaft connecting with the smaller portion of said first 10 named bore, a piston mounted on said reduced portion of said shaft, the end of said shaft being riveted over to hold said piston in position, and a small passageway formed in said shaft inwardly of said piston and communicating with the larger 15 portion of said first named bore.

3. A dash pot plunger device comprising a shaft having a longitudinal orifice extending into an end portion thereof, a transverse bore in said shaft and communicating with said orifice, a 20 piston on said end of said shaft and spaced toward said end from said bore, a valve seat in said orifice, a valve associated with said seat, and a second transverse bore in said shaft and communicating with said orifice on the opposite side 25 of said valve seat from said first mentioned bore, the smaller cross sections of said transverse bores being of substantially different sizes whereby fluid may pass through one of said bores more easily than through the other. 30

4. In a carburetor, a throttle valve, a throttle valve shaft, an accelerating pump, means for connecting said throttle valve and said pump comprising in part a lever rigidly mounted on said 35 throttle valve shaft, a dash pot device including a plunger, a lever loosely mounted on said throttle valve shaft, means for connecting said dash pot plunger to said loosely mounted lever, means for connecting said loosely mounted lever to said rigidly mounted lever for non-yielding movement 40 of said dash pot plunger in one direction during closing movement of said throttle valve, and yielding means connecting said lever for movement of said plunger in the other direction during opening movement of said throttle valve. 45

5. The combination of elements specified in 50 claim 4 in which said dash pot device includes bypass structure whereby said device applies substantially greater resistance to closing movement of said throttle than to opening movement of said throttle.

6. The combination of elements specified in 55 claim 4 in which said accelerating pump is arranged to resist closing movement of said throttle valve in addition to the resistance offered to such movement by said dash pot plunger.

7. In a carburetor, a throttle valve, and a dash pot device operatively associated with said valve, said device comprising a fluid chamber, a plunger formed of a piston rod and a piston movable in 60 said chamber, there being a longitudinal orifice in said rod opening into said chamber on both sides of said piston, and a check valve in said orifice, said check valve being arranged to close said orifice when said piston is moved in one direction 65 whereby said device substantially retards corresponding movement of said first mentioned valve.

8. The combination of a carburetor having a 70 throttle valve, actuating mechanism for said throttle valve including means for normally moving the valve towards closed position, a retarding device, means connecting the retarding device with said throttle actuating mechanism for moving said device to its operative position during predetermined movements of said mechanism, 75.

and means for connecting said retarding device and said throttle valve only during the final portion of the closing movement of said valve for retarding the latter.

5 9. The combination of a carburetor having a normally closed throttle valve, means for opening said throttle valve, a normally inoperative re-

tarding device, means actuated by the valve opening mechanism for moving the retarding device into operative position, and means for connecting the retarding device with the throttle valve during a predetermined period of its movement. 5

OTTO HENNING.
